UNITED STATES PATENT OFFICE.

FRANK BEMENT, OF WORCESTER, MASSACHUSETTS, ASSIGNOR TO THE WIRE GOODS COMPANY, OF WORCESTER, MASSACHUSETTS, A CORPORATION OF MASSACHUSETTS.

GARMENT-HANGER.

No. 842,982.

Specification of Letters Patent.

Patented Feb. 5, 1907.

Application filed August 18, 1904. Serial No. 221,305.

To all whom it may concern:

Be it known that I, FRANK BEMENT, a citizen of the United States, residing at Worcester, in the county of Worcester and Commonwealth of Massachusetts, have invented a new and useful Improvement in Garment-Hangers, of which the following is a specification, accompanied by drawings forming a part of the same, in which—

10 Figure 1 represents a front view of a garment-hanger embodying my invention. Fig. 2 is a top view. Fig. 3 represents my improved hanger in a folded position. Fig. 4 is a detached view of one of the folding arms, 15 and Fig. 5 is a detached view of the suspension-hook.

Similar reference figures refer to similar parts in the different views.

The object of my invention is to provide a 20 garment-hanger in which the supporting arms and suspension-hook when extended to hold a garment will form a firm and rigid structure, but capable of being folded when not in use to render the garment more compact and portable; and it consists in the construction and arrangement of parts, as hereinafter described, and pointed out in the annexed claim.

Referring to the accompanying drawings, 30 11 denote the garment-supporting arms, preferably formed of wire and of duplicate construction, one of said arms being shown in detached view in Fig. 4. Each arm is formed from a single piece of wire, which is 35 bent upon itself near its central section to form an open loop 2, adapted to extend under the shoulders of the garment, said loop 2 being sufficiently open or extended to form a broad bearing-surface for the garment. The 40 two ends of the wire converge from the loop 2 toward the center of the hanger and are twisted together at 3 to firmly unite the opposite ends of the wire and prevent their spreading. The end 4 of the wire extends toward the center 45 of the hanger in a horizontal line and is upturned at 5, said upturned tip 5 being preferably slightly flattened, so as to present a contacting surface for the duplicate opposing tip 5 of the opposite arm. The opposite end 50 of the wire 6 is bent upward at an oblique

angle to the end 4 and terminates in an eye 7. The eyes 7 upon each of the arms are strung upon a pin 8, which forms a pivotal pin upon which the arms 11 are capable of turning to allow the hanger to be folded into the position shown in Fig. 3. The hanger is suspended from a hook 9, having a curved shank 10 and provided at its lower end with an eye 11, which incloses the pivotal pin 8 between the eyes 7 of the garment-supporting arms. 55 In its extended position adapted for use the several parts of the hanger assume the position shown in Fig. 1, with the two garment-supporting arms 11 extending laterally upon each side of the suspension-hook and held 60 from further downward movement around the pivotal pin 8, when the weight of the garment is supported upon the arms by means of the contacting tips 5, which are arranged to be brought into contact and limit the rocking movement of the arms 11 and hold said arms in proper extended position to support 65 a garment upon them.

In order to fold the hanger, the two arms 11 are rocked on the pivotal pin 8 in the direction of the arrows 12 12, Fig. 1, in order to bring the arms together upon each side of the suspension-hook 9 in the position represented in Fig. 3, in which position the space occupied by the hanger is greatly lessened. 70

What I claim as my invention, and desire to secure by Letters Patent, is—

In a garment-hanger, the combination of a pair of duplicate arms each formed from a single piece of wire bent upon itself to form a 85 loop and being united near its ends, with the ends of each wire slightly separated and with one end bent to form a circular eye, and with the other end bent at an angle and flattened to form a contacting tip opposite the center 90 of said eye, a suspension-hook provided at one end with a circular eye inserted between the eyes of said arms and a pivotal pin passing through and uniting said eyes.

Dated this 15th day of August, 1904.

FRANK BEMENT.
